J. W. HYATT & J. EVERDING,
PROCESS OF MAKING SOLID COMPOUNDS FROM SOLUBLE NITRO
CELLULOSE.

UNITED STATES PATENT OFFICE.

JOHN W. HYATT AND JOHN EVERDING, OF NEWARK, N. J., ASSIGNORS TO
THE CELLULOID MANUFACTURING COMPANY, OF NEW YORK, N. Y.

PROCESS OF MAKING SOLID COMPOUNDS FROM SOLUBLE NITRO-CELLULOSE.

SPECIFICATION forming part of Letters Patent No. 326,119, dated September 15, 1885.

Application filed June 26, 1885. (No model.)

To all whom it may concern:

Be it known that we, JOHN W. HYATT and JOHN EVERDING, both of the city of Newark, in the county of Essex and State of New Jersey, have invented new and useful Improvements in the Process of Making Solid Compounds from Soluble Nitro-Cellulose, of which the following is a specification.

Our invention relates to a new process for 10 making solid compounds from soluble nitro-cellulose by first treating the nitro-cellulose with spirits of camphor or other solvents, and afterward by heat and pressure, as well known in the art; but our invention relates more especially to that part of the process where the 15 solvents are mixed with the nitro cellulose.

It is a well-known fact that it has heretofore been practically impossible to mix the nitro-cellulose or pyroxyline with spirits of camphor, so as to produce good and uniform results, and it has always been attended with a serious waste of the solvents employed.

The object of our invention is to provide an apparatus wherein the pyroxyline pulp can 25 be thoroughly and successfully mixed with the proper quantity of solvents.

To this end our improvements consist in introducing the solvent, in the form of a spray, in a cylindrical vessel which is partly filled 30 with the pyroxyline pulp, and provided with a rotary sweep or agitator for the purpose of stirring up the mass. The pyroxyline is first ground into a pulp in an ordinary beating-engine or pulp-mill, and it is then dried in an 35 isolated building on account of the inflammable character of the material. When thoroughly dried, it is taken in small lots or batches to the mixing apparatus shown in the accompanying drawings, of which—

40 Figure 1 is a transverse section of the apparatus, an outside view of the pump which supplies the solvent, and a vertical central section through the tank containing the solvents; and Fig. 2, a central longitudinal section 45 of the apparatus embodying our improvements.

A is a cylindrical vessel with the ends closed and made in halves, the lower half being mounted in suitable supports, A' A'. This vessel contains a sweep or frame, B, provided

with trunnions B' B', and rotated by means of 50 a pulley, B², in bearings A² A², which are part of and pass through the center of the cylinder A. The outer edges of the frame B are provided with a number of projections or teeth, 55 b b b, which mesh and correspond with stationary teeth a a a, secured to the inner periphery of the cylinder A. A finely-perforated pipe or sprinkler, C, passes through one of the trunnions B', and is held in a central position by a recess or bearing in the opposite end of the revolving frame B. The solvents are supplied to this pipe by a pump, D, which is drawn from a crank-shaft, D'. The action of the pump is coincident with the revolving frame B, both receiving their motion from the 65 main shaft F.

In order to regulate the quantity of solvents to be supplied to the spray-pipe C, the stroke of the pump may be lengthened or shortened by moving the crank-pin toward or from the 70 center of the crank-shaft, or any other suitable means.

The pump is connected with a tank, E, which contains the solvents, by a pipe, e; and to prevent any foreign substance from passing 75 through the pump and obstructing the openings in the spray-pipe, this pipe e is provided with a strainer, e'.

A gage may be attached to this tank to determine the exact quantity of solvents used at 80 any time during the operation.

The cylinder A is made in halves, or provided with a large opening and corresponding door, to permit the introduction of the pyroxyline pulp and the removal of the mass 85 when thoroughly mixed.

The operation is as follows: The cylinder A is partly filled with the dry pyroxyline pulp, closed, and the agitator and pump set in motion. After the proper quantity of the solvent 90 has been injected by the pump the agitator is kept running a short time, until the mass is thoroughly mixed. The mass is then removed from the cylinder and placed in an air-tight box for a period of two to three days, 95 when it is ready for conversion in masticating-rolls or otherwise, as required.

We prefer to construct the apparatus as

shown and described; but it is obvious that it may be changed or modified without departing from the spirit of the invention—as, for instance, the vessel containing the pyroxylene pulp may be a tumbling-barrel; or, in other words, the vessel may be made to revolve around a stationary sweep or agitator; or the machine may be so constructed that the cylinder and agitator revolve in opposite directions.

10 We are aware that pyroxylene has been heretofore subjected to the action of spirits of camphor or other solvents, and do not, therefore, broadly claim such process; but to our best belief and knowledge no successful means or apparatus have until now been devised to accomplish satisfactory results in economically, uniformly, and thoroughly mixing the materials.

15 What we do claim, and desire to secure by Letters Patent, is—

1. A machine for mixing pyroxylene in a finely-divided state with spirits of camphor or other solvents, consisting of the combination of a vessel wherein the pulp is stirred, substantially as described, and a perforated pipe 25 or sprinkler by which the solvents are sprayed upon the pyroxylene pulp, substantially as described.

2. In a machine for mixing pyroxylene pulp with spirits of camphor or other solvents, a 30 cylindrical vessel to be partly filled with pyroxylene pulp, a sweep or agitator for stirring up the pulp, and a spray pipe or sprinkler supplied by a pump, substantially as described.

JOHN W. HYATT.
JOHN EVERDING.
